ATTORNEY

UNITED STATES PATENT OFFICE

HERMAN J. HAMMERLY, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT

ELECTRIC SWITCH BOX LATCH AND HANDLE

Application filed October 10, 1931. Serial No. 568,024.

My invention relates particularly to what are sometimes called safety switches and especially to the fuse door and latch for such a switch.

Such switches are usually mounted on the wall and it is quite desirable to provide a cover portion or door for the fused end of the switch and which door will automatically close when released and which will automatically latch when closed. It is also desirable that the operator be able to release the latch and open the door with one hand.

I have sought to provide a construction of this character which is simple, inexpensive and yet easily operative and effective.

In carrying out this object I have provided a construction in which the door has a latch member which is pivoted to the lower edge of the door and normally interlocked with a stud or projection in the body of the box. This latch is provided with a projecting operating handle and with means for sealing or locking the door closed. This latch is so constructed and mounted as to be readily operable by the fingers of one hand at the same time that the hand is used to raise the door, thus leaving the other hand of the operator free to remove and replace the fuses.

Fig. 1 is a perspective view of a construction embodying my invention and showing the door closed.

Fig. 2 is a vertical sectional view showing the door partially opened.

Fig. 3 is a perspective view showing the latch and fragmentary portions of the door and box.

The box 5 may be of any suitable construction and is preferably provided with a cover formed in two parts, namely, the upper part 6 which is normally stationary and the lower part 7 which is hinged at 8 to the upper part and forms the door to the fuse chamber. The upper part may be suitably secured to the box body, for instance, by a number of screws such as 9—9. The cover is also preferably provided with a flange 10 which surrounds the outer edge of the box body.

The switch per se (not shown) may be of any suitable construction and provided with suitable external means for operating the

same as, for instance, the handle 11 which is pivoted to the upper part of the cover.

The catch proper may be formed of sheet metal and is provided with a hook like inner portion 12 and is hinged to the stud 13 on the lower flange of the door. The latch is provided with a handle or finger piece 14 of suitable shape to facilitate grasping and operating the same. The latch is also preferably provided with a perforated ear portion 15 for the attachment of a sealing wire, padlock or other locking device. The door is provided with a slot 16 through which the handle and the locking ear are movable.

The body of the box is provided with a projecting stud 17 with which the hook 12 of the latch is adapted to interlock when the door is closed. The edge of the box is notched at 18 to allow clearance for the pivot stud 13 of the latch. A spring 19 is interposed between the inner wall of the door and a portion of the latch member so as to yieldingly bias the latch toward the locking position. The latch is provided with an inclined nose 20 adapted to engage the stud 17 as the door is being closed so as to automatically retract the latch and permit the door to be closed whereupon the spring moves the latch to the locking position as shown in Fig. 3.

To release the latch and open the door it is simply necessary to rotate the latch clockwise as viewed looking down upon the latch so as to disengage the hook 12 from the stud 17 whereupon the door may be raised by pulling downwardly on the latch assisted if necessary or desired by the engagement of the fingers beneath the flange of the door.

This construction greatly facilitates the opening of the door and is of great importance in structures of this character where the door frequently closes and requires considerable force to open it.

It will be seen that when the door is released it will fall by gravity so as to automatically reengage the latch with the stationary stud.

I have shown and described the latch as mounted at the lower end of the box for the reason that this construction has the advantage that gravity tends to cause the cover to

drop into closed position and thus cause the automatic engaging movement of the latch, but the latch may be mounted at the upper end of the box if so desired and without departing from the broad spirit of my invention.

I claim:

1. A switch box having a door hinged thereto, said door having a flange overlapping outside the edges of the box, a latch pivoted to the flange of the door, an inwardly projecting rounded stud carried by a wall of the box adjacent one edge thereof for engagement by the latch when the door is closed, and a spring for automatically forcing said latch into latching engagement with said stud, said latch having an externally projecting operating fingerpiece, said flange adjacent said latch providing a finger-hold adjacent the finger-piece of said latch.
2. A switch box, a door hinged to said box and having a flange for overlapping outside the edge of said box, a stationary projection carried by the inner wall of the box adjacent the edge thereof, a latch pivotally carried by said door and having a hook portion, a spring for forcing said latch into position for automatically engaging the hook portion with said projection when the door is closed, said latch having an external projecting finger-piece located adjacent the edge of said flange so as to permit simultaneous engagement of the fingers with the edge of the flange and the fingerpiece so that the latch may be retracted and the door opened by the fingers of one hand.

HERMAN J. HAMMERLY.
